PORTEMONNAIE

Leon Mayer, Chicago, Ill.

Application May 3, 1936, Serial No. 77,513

4 Claims. (Cl. 150—35)

This invention relates to portemonnaies or pocket books of the type adapted to carry bills, coin and an owner's identification card.

A known type of such portemonnaie consists of a flexible outer leather or cloth cover of a generally rectangular form that is folded on a central transverse line, such fold forming an integral hinge, and enclosing when folded a coin receptacle and/or a bill fold, and means for separably locking the two halves in folded position.

My present invention has to do with portemonnaies or pocket books of this general type, and its general object is to provide improvements in the structural features of such articles as will render them more durable, compact, capacious and convenient in use, and in which all of the various articles carried thereby will be kept separate from each other and any article can be removed without danger of losing any other article. More specific objects are, to provide an improved form of bill fold, to provide in association with the bill fold, a flap beneath which the bills may be inserted edgewise to keep them from readily dropping out or falling apart when the bill fold is opened, to provide between the bill fold and the cover a convenient pocket for an owner's identification card and to provide in the upper side of said pocket a window through which the card is visible when the bills have been removed.

Other objects and attendant advantages of the invention will be apparent to persons familiar with portemonnaies of this type from the following description, taken in connection with the accompanying drawing in which I have illustrated one approved embodiment of the invention well adapted to effectuate the stated purposes and objects thereof, and wherein—

Fig. 1 is a plan view of the device with the body and bill fold both in open position.

Fig. 2 is a section on the line 2—2 of Fig. 1.

Figs. 3 and 4 are sections at right angles to the section of Fig. 2 on lines 3—3 and 4—4 respectively of Fig. 2.

Fig. 5 is an enlarged fragmentary section in the same sectional plane as Fig. 3, showing the flexible bill confining flap turned back and illustrating its mode of attachment to one edge of the bill fold.

Fig. 6 is a perspective detail view of the bill fold blank.

A backing member 10 of generally rectangular form and a lining 11, united by a continuous line of stitching 12 constitute the cover of the portemonnaie or purse. Between the margins of the

backing and the lining is inserted a fabric strip 13 united by the same stitching 12 which carries the teeth 14 of a "zipper" closure. The cover is foldable on its central transverse line as a hinge to form mating halves designated as entireties by 5 15 and 16.

On the inner side of the half 15 is mounted a bill fold, shown in perspective detail in Fig. 6 and comprising a central portion 17 and right and left foldable wings or flaps 18 and 19 continuous with the opposite edges of the central portion 17. This central portion 17 of the flap is fastened to the lining 11 of the left section by a line of stitching 20 extending along three sides thereof, the fourth side being left open for the 15 insertion of an identification card 21 or the like bearing the name and address of the owner, and the central section 17 is cut out to form a window opening 22 above the card. The face of the card is preferably protected from soiling by 20 the overlying bills by a transparent window 23, preferably of celluloid, that is secured in position along three edges by the stitching 20. On one end of the central portion 17 of the bill fold is an integral extension 24 that, as shown in Fig. 1, 25 is folded inwardly to form a hem, and between the hem and the underlying body portion of the bill fold is inserted an end edge portion of a flexible transparent flap 25, also preferably of celluloid, that is secured at one edge by the stitching 20, as 30 best shown in Fig. 5. The function of this flexible flap 25 is to lie across the central portion of one or more bills indicated at B in Fig. 5 to hold the bill or bills against accidental escape when the bill fold is opened. Preferably the hinged end of the 35 flap 25 is also adhered to the hem 24 by cement 26. Where a strip or sheet of celluloid is attached solely by stitching, and is repeatedly bent on the stitching as a hinge, it soon cracks and breaks, and is thus short lived. I have found 40 that by attaching the celluloid flap 25 in a manner and by the means above described, when it is bent back to permit removal of the bill or bills, it takes substantially the form shown in Fig. 5 and thus avoids the destructive sharp bend above referred to.

On the outer side of the top bill fold flap 18 is mounted the male element 27 of a glove fastener, that cooperates with the female member 28 mounted in a tab 29 attached to the cover by 50 the stitching 12, whereby the bill fold with the bills therein is normally maintained locked in folded position.

On the other half 16 of the portemonnaie is mounted a coin receptacle. This preferably takes 55

the form of an envelope formed with a back wall 30, and a front wall 31, united on three sides by the stitching 12, which of course secures them to the cover. As shown in Fig. 4, the side walls of the envelope are formed with bellows folds 32 to enlarge the capacity of the receptacle, and on the free edge of the back wall is an integral closing flap 33 overlapping the free edge of the front wall 31, said flap and front wall being equipped with the two members 34 and 35 of a glove fastener. The edge of the back wall 30 carrying the flap 33 is left unsecured to the cover lining 11, so that between the latter and the back wall 30 is formed a pocket which may be used for the reception of stamps, cards, and other flat articles.

The cover backing and lining, the bill fold, and the coin receptacle are preferably made of a high grade of soft leather which, of course, is highly flexible transversely, so that the capacity of the article for bills, coins, stamps, cards and the like is considerable; and, when the two halves are unfolded to remove either a bill or coin, either the bill fold or the coin pocket may be opened without disturbing the locked position of the other. The flexible bill retaining flap 25 is a valuable adjunct of the article since, when the bill fold is opened, it keeps the bills from readily dropping out or falling apart enabling one or more to be readily slipped out without disturbing the others.

Changes in the details of structure and arrangement may be resorted to within the purview and scope of the claims.

I claim:

35. 1. A portemonnaie of the type described, comprising a generally rectangular cover foldable on its transverse center line to form mating halves, and comprising a backing and a lining for said backing stitched along its edges to the latter, a bill fold including a single sheet of material having a window opening in its central portion and stitched on three sides of said window opening to the lining of one of said halves to thereby form a card pocket and having end flaps foldable on each other above said central portion, and a flap 40 attached at an edge thereof to an edge of said bill fold above said window opening and adapted to overlie a bill or bills lying on said bill fold.
45. 2. A portemonnaie of the type described, comprising a generally rectangular cover foldable on

its transverse center line to form mating halves, and comprising a backing and a lining for said backing stitched along its edges to the latter, a bill fold including a single sheet of material having a window opening in its central portion and 5 stitched on three sides of said window opening to the lining of one of said halves to thereby form a card pocket and having end flaps foldable on each other above said central portion, and a transparent flexible flap stitched at one edge thereof 10 to an edge of said bill fold above said window and adapted to overlie a bill or bills lying on said bill fold.

3. A portemonnaie of the type described, comprising a generally rectangular cover foldable on its transverse center line to form mating halves, and comprising a backing and a lining for said backing stitched along its edges to the latter, a bill fold including a single sheet of material having a window opening in its central portion and 15 stitched on three sides of said window opening to the lining of one of said halves to thereby form a card pocket and having end flaps foldable on each other above said central portion, a transparent window beneath said opening attached at 20 an edge thereof to and between said bill fold and lining, and a flap attached at an edge thereof to an edge of said bill fold above said window opening and adapted to lie across a bill or bills lying 25 on said bill fold.

4. A portemonnaie of the type described, comprising a generally rectangular cover foldable on its transverse center line to form mating halves, and comprising a backing and a lining for said 35 backing stitched along its edges to the latter, a bill fold including a single sheet of material having a window opening in its central portion and stitched on three sides of said window opening to the lining of one of said halves to thereby form a card pocket and having end flaps foldable on each other above said central portion, a flexible 40 transparent window beneath said opening stitched at an edge thereof to and between said bill fold and lining, and a transparent flexible flap stitched at an edge thereof to an edge of said bill fold 45 above said window opening and adapted to lie across a bill or bills lying on said bill fold.

LEON MAYER.
